CLAIM

The ornamental design for an appendage-worn emergency air canister with safety leash, as shown and described.

DESCRIPTION

FIG. 1 is a perspective view of an appendage-worn emergency air canister with a safety leash attached showing my new design;

FIG. 2 is a right side view thereof;

FIG. 3 is a left side view thereof;

FIG. 4 is a front view thereof;

FIG. 5 is a rear view thereof;

FIG. 6 is a top plan view thereof; and,

FIG. 7 is a bottom plan view thereof.
